UNITED STATES PATENT OFFICE.

JOHN A. GRONOW, OF BROOKFIELD, ILLINOIS.

COMBINATION STEPLADDER.

Application filed December 5, 1925. Serial No. 73,440.

This invention appertains to ladders and more particularly to a novel ladder which can be used for a number of different purposes and which can be folded, so as to occupy a minimum amount of space, when the same is not in use thereby facilitating the transporting and storing thereof.

Another object of the invention is the provision of an improved ladder of novel construction, so arranged and made as to permit the same to be readily used as a tall step ladder for high work, when in one position; as a relatively short ladder when in one of its folded positions, and as a stair ladder when the same is in another one of its set up positions.

A further object of the invention is the provision of a novel sectional step ladder embodying novel hinge members for the front and rear portions thereof, so as to permit the ready folding and collapsing of the ladder and to give strength and rigidity to the ladder at the pivot point of the sections thereof.

A still further object of the invention is to provide an improved folding sectional step ladder of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which drawings:

Figure 1 is a side elevation of the improved step ladder showing the same in one of its set up positions and used as a relatively tall ladder, such as for ceiling work.

Figure 2 is a front elevation of the improved step ladder showing the same in use as a relatively tall ladder,

Figure 3 is a large fragmentary detail sectional view illustrating one method of connecting the steps of the ladder to the side rails thereof,

Figure 4 is a side elevation of the ladder showing the same in its partially folded position for use as a relatively short ladder, for wall work and the like,

Figure 5 is a front elevation of the ladder showing the same used as a relatively short ladder,

Figure 6 is an enlarged fragmentary side

elevation of the front portion of the ladder showing the novel type of hinge employed.

Figure 7 is a fragmentary front elevation of the front portion of the ladder illustrating the novel type of hinge employed,

Figure 8 is a detail perspective view of one of the side plates of the hinge,

Figure 9 is a side elevation of the improved ladder showing the same in use as a stair ladder,

Figure 10 is a detail edge elevation of one of the side rails of the rear portion of the ladder illustrating the novel type of hinge employed for connecting the sections of the rear portion of the ladder together,

Figure 11 is a fragmentary side elevation of one of the rails of the rear portion of the ladder illustrating the novel type of hinge employed for connecting the sections of the rear portion of the ladder together,

Figure 12 is a fragmentary edge elevation of one of the rails of the rear portion of the ladder illustrating the novel hinge employed for connecting the sections thereof together, the view showing the opposite face of the hinge as illustrated in Figure 10,

Figure 13 is a detail elevation of the novel key or pin employed for the hinges for holding the same against normal swinging movement,

Figure 14 is an elevation of the novel pin or key taken at right angles to Figure 13 and showing the movable portion of the key in its operative position for preventing withdrawal thereof from the hinge when the same is in place.

Referring to the drawings in detail, where-in similar reference characters designate corresponding parts throughout the several views, the letter A generally indicates the improved step ladder which is particularly adapted for use by painters, interior decorators and the like but which is susceptible for use in other kinds of work.

The novel step ladder A comprises the front main portion B and the rear portion C and these portions B and C are of substantially the same height and are hingedly connected together adjacent to their upper ends, as will be hereinafter more fully described. The main front section B embodies upper and lower sections 15 and 16, which are connected together at their meeting ends by novel hinges 17, which will be also herein-after more fully described. The rear por-

tion C of the ladder also includes upper and lower sections 18 and 19 and these sections are also connected by novel hinges 20 which will also be hereinafter more fully described.

5 The companion upper and lower sections 15 and 16 of the front portion B of the ladder include longitudinally extending side rails 21 and it is to be noted that the side rails of the lower section 16 below the hinges 17 gradually diverge in order to permit a firm purchase to be had on the ground or floor on which the ladder may be placed. The rails 21 of the sections 15 and 16 are connected together by steps 22 which can be 10 of any desired width and these steps can also be connected to the rails in any preferred way. As shown the inner faces of the rails are provided with notches 23 in which the ends of the steps 22 are placed. The steps 22 at the side rails are braced by transverse rods 24 which extend through the rails directly below the steps so that the steps can rest directly thereon. These rods 24 have the heads thereof countersunk within the outer 15 faces of the rails as clearly shown in Figure 3 of the drawings. As inferred other means can be employed for bracing the ladder and for connecting the steps in place, without departing from the spirit or the scope of this 20 invention.

The hinges 17 are of a novel construction and form an important feature of the present invention. Each hinge 17 includes companion upper and lower sections or leaves 25 35 and 26 and each of these sections or leaves includes inner and outer plates 27 and 28. The outer plates 28 can be provided with inwardly directed flanges 29 for engaging the side edges of the rails and are adapted to be connected to the rails by suitable bolts 30. The flanges can be eliminated on the inner plates 27. The inner ends of the inner and outer plates of the sections of the hinge are provided with oppositely extending rounded 40 ears 31 which are adapted to align with one another. By referring to Figure 7 of the drawings, it can be seen that the ears 31 of one of the lower plates, and the ears of one of the upper plates can be offset in order 45 to insure proper engagement of the ears with one another. The inner ears 31 are provided with aligned axially disposed openings 32 for the reception of a pivot pin 33 and this pivot pin can be of a removable nature if preferred. 50 By this construction it can be seen that the upper section 15 can be swung down on the lower section 16 of the front portion of the ladder. The front ears 31 of the lower section 26 of the hinge are preferably provided 55 with axially disposed polygonal shaped openings 34 for removably receiving the locking pin or key 35, which is clearly shown in Figures 13 and 14 of the drawings. It is to be noted that each key or pin 35 embodies a shank 36 having the head 37 formed

on one end thereof and that the opposite end of the shank is slotted or bifurcated as at 38 for the reception of the reduced flat portion 39 of the swinging detent 40 of the pin. The reduced portion 39 of the detent is 70 received within the slot 38 of the shank and is pivotally connected to the shank at a point intermediate its ends by the use of a suitable rivet or the like 41. When it is desired to hold the sections 15 and 16 of the ladder 75 against swinging movement relative to one another the key or pin 35 is inserted through the aligned openings 34 of the front ears 31 of the sections of the hinge and it is obvious that the hinge will be locked against swinging movement and that an exceptionally strong connection will be had between the sections of the front portion of the ladder. After the keys or pins 35 have been inserted in place the detent portions 40 thereof are 80 swung at right angles as shown in Figure 14 and the upper and lower ends thereof will lie on opposite sides of the openings 34 and thus accidental displacement is prevented.

The sections 18 and 19 of the rear portion 90 of the ladder C are substantially the same length as the upper and lower sections 15 and 16 of the front portion of the ladder. These sections 18 and 19 also each includes the side rails 42 which are preferably braced by diagonal struts 43 which can be connected to the side rails 42 in any desired way, such as bands 44, which as shown embrace the side faces of the rails. The hinges 20 also form an important part of the invention and each hinge includes the upper and lower leaves or sections 45 and 46 and each of the leaves or sections 45 and 46 consists of inner and outer plates 47 for embracing the side faces of the rails 42. Certain of the plates 47 can be provided with inwardly directed flanges 48 for engaging the side edges of the rails and these flanges are connected to the rails by bolts 49. The inner ends of the plates 47 are provided with inwardly directed offset pivot ears 50 which are provided with aligned axial openings for the reception of a pivot bolt 51 on which can be threaded a winged nut 52 in order to firmly bind the hinge together to prevent accidental swinging movement thereof. The inner edges of the plates can also be provided with overlapping laterally extending ears 53 which are provided with suitable openings for the reception of one of the locking keys or pins 35. This also holds the 110 hinge against accidental swinging movement.

The means employed for connecting the front portion B of the ladder to the rear portion C embodies plates 54 which are bolted as at 55 to the upper ends of the rails 21 of the front portion B. These plates 54 can carry suitable pivot bolts 56 which extend through suitable openings in the upper terminals of the rails 42 of the rear section C. Any desired type of retaining means can be em- 130

ployed for holding the rails 42 on the said pivot bolts. By this construction, the portions B and C of the ladder are pivotally connected together and it is to be noted at this 5 point that the portion C is utilized as a rest or support for the main front portion B of the ladder. In order to prevent breaking of the sections of the ladder or the spreading thereof when the ladder is in use, flexible 10 chains 57 are employed for connecting the portions B and C of the ladder together as clearly shown in Figures 1, 4 and 9 of the drawings. These chains can be permanently connected to one of the pins 35 while the other 15 pin can be employed for fitting through any one of the links of the chain so that the active length of the chain can be regulated.

When it is desired to use the ladder for 20 relatively high work the ladder is set up as shown in Figures 1 and 2 of the drawings and the pins 35 are placed in engagement with the 25 hinges 17 and 20 which secures the rigidity of the ladder. The ladder is now ready for use.

When the necessity for a relatively short 25 step ladder arises the ladder is folded as shown in Figures 4 and 5 of the drawings. The folding of the ladder is brought about by swinging the rear portion C on the front 30 portion and by removing the pins 35 from engagement with the hinges 17 and 20. The upper sections 15 and 18 of the front and rear portions B and C are now folded back on 35 their hinges 17 and 20 so as to occupy the position in Figure 4. By this arrangement it can be seen that a relatively short ladder is formed and that the sections of the front portion B of the ladder are disposed on each side, so that a person can mount the ladder 40 from either side thereof.

When it is desired to use the ladder on 45 stair cases and the like the lower sections 19 of the rear portion C of the ladder can be entirely removed by taking out the pivot bolts 50 and the locking keys or pins 35. The front portion B of the ladder is placed on one of the lower steps, while the lower end 55 of the upper section 18 of the rear portion C is placed on one of the upper steps of the staircase. By this arrangement it can be seen that the ladder can be expeditiously used on stairways.

It is to be also noted that the ladder can 60 be folded to a relatively small compass for 55 shipping and storage purposes by simply swinging the portions of the ladder together,

when the same is folded for use as a relatively short ladder, as shown in Figures 4 and 5.

From the foregoing description it can be seen that I have provided a ladder which 60 can be used for a number of different purposes and which is of an exceptionally simple and strong character.

Changes in details may be made without departing from the spirit or scope of this invention, but:

What I claim as new is:

1. In a step ladder of the class described, front and rear ladder structures, means connecting the same at their upper ends for 70 relative angular adjustment, each of said structures comprising an upper and a lower section, hinges connecting the sections of each structure, the hinges connecting the sections of one structure comprising leaf members secured to the said sections and having hingedly connected pintle portions and projecting portions positioned to mutually overlap when the sections are in alined position, means removably engageable with the said 75 projecting portions of the leaf members of each hinge for holding the leaf members against relative movement, and a flexible bracing element extending between each of the hinges of the other ladder structure and 80 adjustably connected with the last mentioned means of the respective hinge of the first mentioned ladder structure.

2. In a step ladder of the class described, front and rear ladder structures, means connecting the same at their upper ends for 90 relative angular adjustment, each of said structures comprising an upper and a lower section, means hingedly connecting the sections of each structure, the hinges connecting the sections of one structure comprising leaf members secured to the said sections and having hingedly connected pintle portions and projecting portions positioned to mutual- 95 ly overlap when the sections are in alined position and provided with openings to register when the sections are in such position, a pin removably fitted through said openings and constituting means for holding the leaf members of the associated hinge against relative movement, and a chain adjustably engaged by each of said pins at one end portion 100 of the chain and having its other end portion connected to the corresponding hinge 105 of the other ladder structure.

In testimony whereof I affix my signature.
JOHN A. GRONOW.
